a corporation of New York

Application February 1, 1944, Serial No. 520,616

14 Claims. (Cl. 172—239)

1

This invention relates to control systems, more particularly to systems for controlling the starting operations of electric motors, and it has for an object the provision of a simple, reliable, and improved control system of this character.

More specifically, the invention relates to motor control systems in which direct current is supplied to a motor through electric valve apparatus and in which provision is made for reversing the direction of rotation of the motor, and a further object of the invention is the provision of means for effecting the reversal of the motor in a minimum of time without damage to the motor.

A more specific object of the invention is the provision of means for effecting successful operation of the electric valve apparatus as an inverter during the reversal period, thereby to eliminate undesirable operating characteristics such as current surges, sparking at the brushes, and violent changes in shaft torque.

A still more specific object of the invention is the provision of means for effecting successful inverter operation of the electric valves during the stopping operation of the motor.

In carrying the invention into effect in one form thereof, suitable electric valve apparatus is provided for supplying direct current to the armature of the motor, together with means responsive to the armature current for controlling the valve apparatus to limit the current to a safe value. Since this current limiting means cannot become effective until current is actually flowing, there is a period following the reconnection of the motor to the supply valve apparatus during a reversal operation in which the current limiting means is ineffective to limit the current. Accordingly, means are provided for preconditioning the control of the electric valve apparatus to limit to a predetermined value the current which can be conducted by the electric valve apparatus at the beginning of the inversion period before the current limiting means becomes fully effective. One form of these means comprises a control valve connected to control the supply electric valve apparatus, a source of standard voltage, reversing switching means for connecting the armature to the supply valve apparatus, and contacts on the reversing switching means for connecting the grid of the control valve in such a manner as to compare the output voltage of the supply valve apparatus to the standard voltage source when the motor is disconnected from the supply valve apparatus, thereby to condition the supply valve apparatus to conduct only a predetermined amount of current when the

2

switching mechanism is reclosed for the reverse direction of rotation. The preconditioning means itself may require a longer time to function than is required by the reversing switching means to reverse the motor connections. Accordingly, a suitable time delay device is provided for preventing the reversing switching means from completing the reversed connections until the preconditioning means has had time to become effective.

10 Additional electric valve apparatus is provided for supplying direct current to excite the motor field. The control of this additional valve apparatus is arranged to excite the field strongly when the directional contactors are open before starting from rest. Means are provided for preventing the strengthening of the motor field during the interval in which the reversing contactors are open during a reversal operation, thereby to limit the armature voltage and to promote a successful inverter operation. Also, means are provided for delaying the strengthening of the field of the motor during the inversion period following the reversal of the connections of the motor armature to the supply valve means until the 20 speed of the motor has been reduced to a predetermined low value.

For a better and more complete understanding of the invention, reference should now be had to the following specification and to the accompanying drawings of which Figs. 1A and 1B are a simple, diagrammatical illustration of an embodiment of the invention.

Referring now to the drawings, an electric motor 10 having an armature 10a and a shunt field winding 10b is supplied from a source of alternating voltage 11 through a supply transformer 12 and suitable electric valve apparatus comprising electric valves 13, 14, 15 and 16. The starting, stopping, and reversing of the motor 10 are under the control of a suitable controlling accessory such as a push-button station 17 and a pair of speed controlling potentiometers 18 and 19. If desired, these speed controlling potentiometers may be mounted on the push-button station control panel.

The secondary winding of the supply transformer 12 is provided with a midtap 12a and this midtap is connected to the bus 20 which becomes the negative side of a D.-C. system, i. e., 50 the negative armature terminal, the negative field terminal, and the negative control terminal. Assuming that the motor 10 is designed for operation on 230 volts, the full secondary voltage of the transformer will be approximately 620 volts. Two 55 57½-volt taps 12b and 12c either side of center

provide a 115-volt center-tapped source of control power for filaments, transformers, phase shift bridges, and relay excitation.

The current supplied to the field winding 10b from the source 11 is controlled by electric valves 13 and 14. As shown, the anodes 13a and 14a of electric valves 13 and 14 are connected by means of conductors 21 and 22 to opposite terminals of the secondary winding of transformer 12. The filamentary cathodes 13b and 14b are heated by 10 means of current supplied to the cathodes through a filament transformer 23, of which the primary winding (not shown) is connected to the 115-volt taps 12b and 12c of the supply transformer, and the secondary winding 23a is connected to the filamentary cathodes 13b and 14b. The secondary winding 23a is midtapped and the midtap is connected to the conductor 24 which thus becomes the positive terminal of the field supply. Thus, the field circuit may be traced from the positive conductor 24 through the normally open contacts 25a of a time delay relay 25, the operating winding 26a of a field loss protective relay 26, through field winding 10b to the negative conductor 20.

The supply of current from the source 11 to the armature 10a of the motor is controlled by means of the electric valves 15 and 16. As shown, the valves 15 and 16, like the electric valves 13 and 14, are connected for biphasic rectification, i. e., their anodes 15a and 16a are connected through primary windings 27a and 27b of a special current transformer 27 to the opposite terminals of the secondary winding of the supply transformer 12. The cathodes 15b and 16b of valves 15 and 16 are provided with suitable heating units which are connected to the secondary winding 23b of the filament transformer 23. The cathodes 15b and 16b are connected to the terminal 28 which thus becomes the positive side of the supply for the armature. Thus the armature circuit is readily traced from the positive terminal 28 through conductor 29, series field winding 10c, one or the other of the directional contactors 30, 31, a heating element 32a of an overload protective relay 32, through the armature 10a, commutating field winding 10d to the negative supply bus 20.

Although the electric valves 13, 14, 15, and 16 may be of any suitable type, they are preferably grid-controlled, mercury-vapor thyratron tubes. The cathodes 15b and 16b of the valves 15 and 16 which control the supply of current to the armature are indirectly heated, and these valves are provided with shield grids 15c and 16c as well as with control grids 15d and 16d, respectively. The valves 13 and 14 which control the supply of current to the field windings have directly heated filamentary cathodes and have only single grids 13c and 14c which are control grids. In thyratron valves, the function of the control grid is only to initiate the flow of current between the anode and cathode during each positive half-cycle of anode voltage. Once current has started to flow in the anode-cathode circuit, the grid exercises no further control until the flow of current through the valve has been interrupted by some means external to the valve itself. Once the current has ceased to flow, the potential of the grid will again determine the point in the positive half-cycle of anode voltage at which the valve will again become conducting. Thus, by varying the firing point, the average value of current flowing in the anode-cathode circuit can be controlled. These valves are therefore grid-controlled arc rectifiers.

The purpose of the time delay relay 25 is to allow time for the initial heating of the cathodes of the electric valves before power is applied to the anode-cathode circuit. Since normally open contacts 25a of the time delay relay 25 are included in the energizing circuit of the field loss protective relay 26, which has normally open contacts 26b in the energizing circuit of the directional contactors 30 and 31, the latter cannot be closed to complete the power circuit of the electric valves until a predetermined interval of time after the connection of the supply transformer 12 to the source of alternating voltage 11.

The purpose of the field loss protective relay 26 is to delay the application of voltage to the armature of the motor until a safe field excitation has been established and to interrupt the armature circuit in case of a field failure.

Although the thyratron valves 13, 14, 15, and 16 may be controlled by any suitable method, it is preferred to use the method of phase shift control of the grid voltage. For the carrying out of this method of control, a pair of phase shifting networks, one for the armature thyratrons and one for the field thyratrons, is provided. The phase shifting network for the armature thyratrons comprises a resistor 33 and the alternating-current winding 34a of a saturable core type reactor 34, and the network for the field thyratrons comprises a resistor 35 and the alternating-current winding 36a of a saturable core type reactor 36. Both these networks are connected in parallel across the low voltage terminals 12b, 12c of the supply transformer. The primary winding 37a of a grid transformer 37 is connected between the midtap 12a and the junction point 33a of the resistor 33 and reactor winding 34a. This grid transformer has two secondary windings 37b and 37c. The secondary winding 37b is connected between the cathode and control grid of armature thyratron 15, and similarly the secondary winding 37c is connected between the cathode and control grid of the armature thyratron 16. A corresponding grid transformer 38 is provided for the field thyratrons 13 and 14. It has a primary winding 38a connected between the midtap 12a and the junction point 35a of the resistor 35 and reactance winding 36a, and a pair of secondary windings 38b and 38c which are connected between the cathode and grid of the thyratrons 13 and 14, respectively. The phase shift of the grid voltages is produced by varying the reactance of the saturable core reactors, which is accomplished by varying the D.-C. saturation of these reactors.

The control is such that when the saturable reactors are saturated, the voltages of the grid transformers are advanced to the in phase position with respect to the anode transformer voltage, and when the reactors are unsaturated, the voltages of the grid transformers tend to be out of phase and lagging. Intermediate values of saturation produce intermediate phase relationships. Thus, when the saturable reactors 34 and 36 are fully saturated, the thyratrons 13, 14, 15, and 16 are fully conducting, and conversely, when the reactors are unsaturated, the thyratrons are nonconducting. For intermediate values of saturation, the thyratrons have corresponding intermediate values of conductivity.

The push-button station 17 is provided with a plurality of push-button type switches 39, 40, and 41 for controlling the starting, stopping, and direction of rotation of the motor 10. The push-button switch 39 controls the starting of the motor in the forward direction; the push-button

switch 43 controls the starting of the motor in the reverse direction; and the push-button switch 41 controls the stopping of the motor.

To the low voltage taps 12b and 12c of the supply transformer is connected the primary winding 42a of a control voltage supply transformer 42. The opposite terminals of the secondary winding 42b of this transformer are connected to the anodes 43a and 43b of a small double diode rectifier valve 43 which furnishes a separate source of low voltage D.-C. from which the control electric valves are energized. The saturating windings 34b and 36b of the saturable reactors 34 and 36 obtain their energization from this source of direct voltage. This direct voltage is filtered by means of a smoothing reactor 44 and a capacitor 45. The voltage across the capacitor 45 is impressed on a circuit comprising a resistance 46 in series with two glow tubes 47 and 48. These glow tubes 47 and 48 are gaseous discharge devices which operate in that region of their characteristic in which the voltage drop across the discharge supporting electrodes is substantially constant over a wide range of current. The voltage across the points 46a and 43a is fixed at a value which is determined by the type of glow tube used, and within the operating limits of this equipment, this voltage is independent of variations in the A.-C. supply voltage. Any difference in voltage between the voltage drop across the capacitor 45 and the constant voltage across the glow tubes 47 and 48 is absorbed by the resistor 46.

The voltage drop across the glow tube 47 is used to stabilize the voltage of the amplifier valves which are connected between the points 46a and 47a. The voltage drop across the glow tube 48 is the voltage standard with which signal voltages are compared for controlling purposes.

For the purpose of varying the direct current which flows in the saturating winding 34b, a suitable amplifying electric valve 49 is provided. This valve is provided with an anode 49a, a cathode 49b, and a control grid 49c. The D.-C. winding 34b and the valve 49 are connected in series across the glow tube 47. The control of the current through the D.-C. winding of the armature saturable reactor 34 is accomplished by proper choice of the grid-to-cathode voltage of the valve 49. As the voltage of the grid 49c is made less negative with respect to the voltage of the cathode 49b, the current transmitted by the valve increases, thereby increasing the saturation of the armature saturable reactor 34, which, as stated in the foregoing, results in increasing the voltage applied to the armature of the motor 10. Conversely, as the voltage of the grid 49c is made more negative with respect to the voltage of cathode 49b, the current transmitted by the valve decreases and this decreases the voltage supplied to the armature of the motor. An additional amplifying electric valve 50, which is provided with an anode 50a, a cathode 50b, and a control grid 50c, is provided for the purpose of varying the voltage on the grid 49c so that the speed of the motor 10 is maintained constant at a preset value which is correlated with the position of the slider 18a on the speed controlling potentiometer 18. In other words, the electric valve 50 serves as a connecting and amplifying link between the armature speed controlling potentiometer 18 and the electric valve 49 which controls the saturation of the armature saturable reactor 34, and hence, controls the armature voltage and speed of the motor 10. The grid 49c

of valve 49 is connected to a voltage divider comprising resistors 51a, 51b, and 51c. The electric valve 50 is connected between the slider 18a of the speed controlling potentiometer 18 and the junction point of the resistors 51a and 51b. When the voltage of the grid 50c is made less negative with respect to its cathode, the current transmitted by the valve 50 is correspondingly increased, and since this current flows through the resistor 51a, the voltage drop across resistor 51a is correspondingly increased and consequently, the voltage of the grid 49c is correspondingly decreased so that the current transmitted by valve 49 is decreased and the armature voltage and speed are correspondingly decreased. Thus, increasing the conductivity of electric valve 50 has the effect of decreasing the voltage supplied to the armature and conversely, decreasing the current conducted by electric valve 50 has the effect of increasing the voltage supplied to the armature.

Since the lower terminal of resistor 51c and one electrode of glow tube 48 are connected together at point 48a, and since the upper terminal of resistor 51c is connected to the grid 49c, the valve 49 compares the voltage drop across the resistor 51c with the voltage drop across the tube 48.

If the armature voltage or a portion of the armature voltage is impressed on the grid 50c, an increase in armature voltage will increase the conductivity of valve 50, thereby decreasing the conductivity of valve 49 and decreasing the voltage supplied by the thyratrons 15 and 16, thereby to correct for the increase in armature voltage.

If the armature voltage decreases, the reverse action takes place and the decrease in armature voltage is corrected. The position of the slider 18a on the armature speed control potentiometer determines the percentage of the total voltage

drop across the valve 48 which is to be derived and used as a preset indication of speed. The voltage that is so derived and used as a reference voltage is the voltage between the slider 18a and the negative bus 20. Since the cathode of the

valve 50 is connected to the slider, then the position of the slider will determine the voltage of the cathode relative to the negative bus 20. A signal voltage is derived from the armature voltage by means of a voltage divider which comprises resistor 52a, potentiometer 52b, resistor 52c, and that portion of the potentiometer 53 between the slider 53a and the negative bus 20. The signal voltage used is the voltage from the slider 52d to the negative bus 20, and this signal voltage is impressed on the grid 50c of valve 50.

Thus the grid-to-cathode voltage of the valve 50 is the difference between the signal voltage and the voltage from the slider 18a to the negative bus 20. The tendency of the circuit is to maintain the signal voltage approximately equal to the reference voltage, i. e., the voltage from the slider 18a to the negative bus 20. Hence, the armature voltage and the speed of the motor will be approximately proportional to the reference voltage tapped off by the slider 18a of the speed control potentiometer.

The voltage selected by the position of the slider 18a is a portion of the constant voltage across the glow tube 48 and is therefore substantially constant. As the slider 18a is moved from position 0 to position 5, the preselected speed levels are progressively increased. When the slider is at position 5, the maximum voltage can be impressed on the armature of the motor.

For the purpose of varying the saturating cur-

rent of the field saturable reactor 36, a pair of electric valves 54 and 55 corresponding, respectively, in function to the valves 49 and 50 of the armature control, is provided. The electric valve 54 has an anode 54a, a cathode 54b, and a control grid 54c; and similarly, the valve 55 has an anode 55a, a cathode 55b, and a grid 55c. In the control of the field current, the voltage across the shunt field winding 10b is utilized as an indication of field current. The connections and operation of the valves 54 and 55 are similar to the connections and operation of the valves 49 and 50 of the armature control. The electric valves 54 and 55 operate to compare the voltage across the field winding 10b, or a selectable portion thereof, with a reference voltage which is derived from the voltage of the glow tube 48 by means of the slider position on the field control potentiometer 19 which is connected in series with a rheostat 56 across the glow tube 48. The difference between the signal voltage derived from the field winding and the reference voltage derived from the glow tube 48 is impressed on the grid cathode circuit of the valve 55 in such a manner that if the voltage across the field increases, the conductivity of the valve 55 increases, thereby decreasing the conductivity of the valve 54 and the saturation of the field saturable reactor 36, thereby to decrease the voltage supplied to the field winding. Conversely, a decrease in the voltage across the field winding has the effect of decreasing the conductivity of the valve 55, thereby increasing the conductivity of the valve 54 and increasing the field voltage.

The armature speed control potentiometer 18 and the field weakening control potentiometer 19 are preferably combined on a common shaft with the resistance portions 18 and 19 arranged circumferentially and with the sliders so oriented that with the speed control knob in the zero position, which may be assumed to be the full counterclockwise position, the sliders 18a and 19a will also be in the zero position. Thus, when the speed control knob is turned in a clockwise direction from the zero position, the slider 18a of the armature voltage potentiometer taps off an increasing portion of the reference voltage of valve 48, but the slider 19a of the field weakening potentiometer slides along the contact strip 19b and therefore taps off the full voltage of the tube 48 which corresponds to a condition of full field excitation. However, when the control knob passes position 5, the slider of the armature speed control potentiometer slides on the contact strip 18b so that it taps off the full voltage of the tube 48 corresponding to full armature excitation, but the slider 19a of the field weakening potentiometer begins to tap off decreasing portions of the voltage across the tube 48 so that the field is progressively weakened as the movement of the control knob in a clockwise direction continues. In the extreme clockwise position, which is position 9 on the dial, the armature thyratrons 15 and 16 are supplying rated voltage to the armature, and the field thyratrons 13 and 14 are supplying the minimum voltage to the field winding 10b. Therefore, the motor rotates at maximum speed.

For the purpose of limiting the armature current to a maximum permissible value, means are provided for comparing a signal voltage derived from the anode current of the armature thyratrons with a reference voltage and utilizing the difference of these signal and reference voltages to control both the armature and field thyratrons

in such a manner as to limit the armature current to the desired value. These means are illustrated as comprising the anode current transformer 27, the control amplifier valves 57 and 58 and the double diode rectifying electric valve 59. As shown, the two primary windings 27a and 27b of the anode current transformer are connected in series with the anode circuits of each of the armature thyratron valves, and this transformer is polarized in such a manner that when one of the armature thyratrons conducts, the flux in the core is in one direction and when the other thyratron conducts, the flux is reversed. As a result, an A.-C. voltage is induced across the secondary winding 27c and the magnitude of this induced voltage is determined for a given value of primary current by the resistance load connected to the secondary and by the turn ratio between primary and secondary windings. This alternating voltage is rectified by the electric valve 59 and appears as a direct voltage across a voltage divider comprising potentiometer resistor 60, fixed resistor 60a, and potentiometer resistor 53.

The electric valves 57 and 58 are provided with anodes 57a and 58a, cathodes 57b and 58b, and grids 57c and 58c, respectively. The anode 57a is connected to the junction point between the sections 51a and 51b of the voltage divider to which the grid of valve 59 is connected, and the cathode 57b of valve 57 is connected to the point 47a to which the cathode 49b of valve 49 is connected. The anode 58a is connected to the conductor 61 and the cathode 58b is connected to the grid 54c of the field control valve 54 which, as shown, is connected to the junction point between the resistance sections 62b and 62c of a voltage divider comprising the resistance sections 62a, 62b and 62c connected across the D.-C. control system buses 61 and 20. The potential at the junction of resistance sections 62b and 62c when valve 55 is regulating the field voltage, is such that the potential of the cathode 58b is slightly more negative than the potential of cathode 57b.

When small amounts of current flow in the armature circuit, the voltage developed across the secondary of the current transformer 27c and the voltage rectified by the valve 59 will be so small that the portion which is utilized as a signal voltage, i. e., the voltage between the slider 60b and the negative bus 20 is substantially less than the voltage across the valve 48, and consequently, the grids of the valves 51 and 58 which are connected to slider 60b are very much negative with respect to their cathodes which are connected to the conductor 47a and to the junction point between the resistance sections 62b and 62c, respectively. An increase of armature current causes the voltage across the secondary of the current transformer 27 to increase, and the voltage rectified by the valve 59 increases correspondingly so that the voltage between the slider 60b and the negative bus 20 ultimately reaches a value approximately equal to the voltage across the valve 48, and the negative grid voltages of valves 51 and 58 are reduced to the value at which these valves begin to conduct current.

When valve 57 conducts current, it has the same effect as if valve 58 were conducting current, which is to decrease the current conducted by valve 49 and thereby decrease the voltage supplied to the armature.

The operation of valve 58 is slightly different

in that its cathode is connected to the grid circuit of the valve 54 instead of to the cathode of valve 47, and its anode is connected to the positive bus 61. When the grid of valve 58 is made sufficiently less negative to cause current to flow in the anode circuit, the effect of current flow through valve 58 is to make more positive the potential of the junction point of the resistors 62b and 62c to which the grid 54c of valve 54 is connected. This has the effect of increasing the conductivity of valve 54 with the result that the field of the motor 10 is strengthened, if it has been in a field weakened condition. Since the cathode 58b is more negative than the cathode 57b of valve 57 for low values of armature current, the valve 54 will be controlled slightly ahead of the valve 49 as the armature current increases, with the result that the field will be strengthened before the armature voltage is decreased. To provide for a range of adjustment, the resistor 60 is made in the form of a potentiometer.

When a motor is operated at rated armature voltage and at maximum rated field current and is carrying rated full load, it is said to be operating at base speed. If the motor 10 is being operated in the field weakened range, e. g., three times base speed, and if then the speed controlling potentiometers 18 and 19 are suddenly changed to a position of lower speed, e. g., one-half base speed, the control would function to decrease the voltage supplied by the armature thyatrons 15 and 16 and to increase the voltage supplied to the field winding by the field thyatrons 13 and 14, as a result of the action of the electric valves 49 and 50, and 54 and 55. With the motor running at three times base speed and full field applied as quickly as the time constant of the magnetic circuit will permit, the tendency is for the armature countervoltage to increase to a value which is approximately three times full terminal voltage, i. e., 750 volts in the case of a 250-volt motor. To prevent such an undesirable increase in the armature voltage, an additional electric valve 64 is provided. This valve is provided with an anode 64a, a cathode 64b, and a grid 64c. The anode 64a of this valve is connected to the junction point of the resistors 62a and 62b of the voltage divider to which the grid 54c of valve 54 is connected, and the cathode 64b of valve 64 is connected to the conductor 47a. The grid 64c of valve 64 is connected to the junction point 65a of two resistors 65 and 66 which, together with the potentiometer 53, constitute a voltage divider connected across the armature of the motor 10. As thus connected, this valve 64 measures a fixed portion of the armature voltage, i. e., a portion between the junction point 65a and the negative bus 20, and when this portion exceeds the voltage drop across the reference voltage valve 48, the valve 64 becomes conducting, thereby to increase the voltage drop across the resistor 62a and decrease the potential of the grid 54c of valve 54, to prevent the saturation of the saturable reactor 36 which controls the field thyatrons 13 and 14. The action of valve 64 upon valve 54 is very similar to the action of valve 55 except that the valve 54 receives its voltage signal from the armature circuit, whereas the valve 55 receives its voltage signal from the field circuit.

In order to promote a rapid and smooth transition from rectifier operation to inverter operation of armature thyatrons 15 and 16 during the reversal period, a preconditioning circuit is provided for controlling the armature thyatrons.

This preconditioning circuit connects the grid 57c of control valve 57 to the junction point 67a of resistors 67 and 68 which constitute a voltage divider connected between the positive side of the standard voltage, bus 61, and the positive side of the output voltage of the armature thyatrons 15 and 16. Included in this circuit are the normally closed interlock contacts 39a and 31a of reversing contactors 30 and 31, respectively. This preconditioning circuit is effective, therefore, only when both reversing contactors are dropped out as during a reversal operation, or when the motor is at rest or is being dynamically braked to rest.

The point 67a on the voltage divider is selected so that at the instant of reconnection of the armature to the thyatrons 15 and 16 during a reversal operation, the phase of the grid voltage of the thyatrons is retarded to a point such that the armature current will not exceed a predetermined safe value, such as approximately full load current. The time required for the preconditioning circuit to effect the retardation usually exceeds the time required for the reversing contactors to reverse the armature connections to the thyatrons. For the purpose of preventing the reversing contactors 30 and 31 from completing the reversing of the armature connections to the thyatrons before the preconditioning operation is sufficiently complete, a suitable time delay device such as the relay 70 is provided. This relay has normally open contacts 70a included in circuit with the operating coils 30c and 31c of the reversing contactors 30 and 31, respectively, and the operating coil 70b of the relay 70 is included in series with normally closed contacts 30b and 31b of the reversing contactors 30 and 31, respectively. As a result of this interconnection, neither of the reversing contactors 30 and 31 can be reclosed during the time following its dropout required for relay 70 to pick up.

Another conditioning circuit is completed by an electric valve 71 of which the anode 71a is connected to the conductor 47a and thus to the cathode 57b of valve 57, and the cathode 71b is connected to the grid 57c of valve 57. The function of valve 71 is to prevent the grid 57c from becoming excessively negative at light motor loads and delaying the response of the current limit control to sudden increases in the armature current.

In order to facilitate motor reversal at field weakened speeds, means are provided to maintain the previous strength of the field during the interval in which both reversing contactors are open during the reversal period and to provide full field strength for starting the motor from rest. To this end, an additional control relay 72 is provided. This relay has a normally closed contact 72a included in circuits between the cathode 55b of field control valve 55 and conductor 47a, and a normally open contact 72b between cathode 55b and slider 19a of the field control potentiometer 19. The relay 72 is also provided with normally open contacts 72c which, when the relay is picked up, complete a sealing-in circuit.

If the strength of the motor field is increased too rapidly following the reconnection of the armature to the supply thyatrons 15, 16 in a reversal from a field-weakened speed, successful inverter operation may be defeated. To prevent this too rapid strengthening of the motor field by the action of valve 58, which operates on valve 54 at high armature currents, a reverse 75 "snubbing" circuit is provided. This reverse

"snubbing" circuit comprises an electric valve 73 having its anode 73a connected to the grid 54c of the valve 54 and having its cathode 73b connected to the junction point 74a of two resistors 74 and 75 which, together with resistor 69, constitute a voltage divider connected across the standard voltage valve 48. The junction point 75a of the resistors 75 and 69 is connected to the common point 76 of the two reversing contactors by means of a conductor 77. The common point 76 of the two reversing contactors is connected to the positive side 28 of the armature supply. The grid 73c of valve 73 is connected to the negative bus 20 and consequently, except when the armature is rotating in a direction opposite to that which corresponds to whichever of the two directional contactors is closed, the grid 73c is so negative with respect to its cathode that valve 73 is non-conducting and has no effect on valve 54 which directly controls the field saturable reactor 36.

During the interval in which both directional contactors are dropped out during a reversal from a given speed in one direction to the same given speed in the reverse direction, the field strength remains constant at the value set on the field potentiometer 19. However, when reversing from a high speed in one direction to a relatively lower speed in the opposite direction, the slider 19a of the field potentiometer 19 is moved to a lower speed position in which current conducted by valve 55 is decreased. This tends to increase the current conducted by valve 54 thereby to strengthen the motor field to such an extent that upon completing the reversal of the armature connections, the voltage generated by the motor is so high as to interfere with successful inverter operation. To overcome this tendency of the control to strengthen the fields during the operation of the directional contactors for a reversal from a higher to a lower speed, an additional electric valve 78 is provided for supplying a voltage to control valve 64 in such a manner as to prevent valve 54 from responding to the potentiometer 19 to strengthen the motor field. Valve 78 is illustrated as a double diode valve having anodes 78a and 78b connected to opposite terminals of the dynamic braking resistor 79 which, when the directional contactors 30 and 31 are dropped out, is connected across the armature terminals by the normally closed contacts 30d and 31d of the directional contactors. The cathode 78c of valve 78 is connected by means of a conductor 80 to the point 65a of the voltage divider to which the grid 64c of the valve 64 is connected.

With the foregoing understanding of the elements and their organization, the operation of the system itself will readily be understood from the following detailed description.

To place the system in condition for operation, the switch 81 is closed to connect the primary winding of the supply transformer 12 to the supply source 11. As a result, the operating coil of the time delay relay 25 is energized and after an interval of time which is determined by the setting of its time delay device, and which is sufficient to provide for initial heating of the cathodes of the electric valves, the time delay relay 25 closes its normally open contacts 25a to complete the field circuit from the cathodes of the field thyratrons 13 and 14 through the operating coil 26a of the field loss protective relay 26 and the field winding 10b to the negative bus 20. As a result of the closing of switch

81, the low voltage control transformer 42 is energized and the full wave rectifier valve 43 supplies a rectified voltage to the buses 61 and 20 which voltage is maintained constant by the standard voltage regulator valves 47 and 48. Since the directional contactors 30 and 31 are open, the operating coil 70b of control relay 70 is connected across the standard voltage conductors 61 and 20 through the normally closed contacts 30b and 31b of the directional contactors. Responsively to energization, relay 70 picks up and closes its normally open contacts 70a and 70c. At this point in the operation, the grid 57c of the current limit control valve 57 is connected through conductor 82 and the normally closed contacts 30a and 31a of the reversing contactors to the point 67a on the voltage dividers 67, 68 such that the current conducted by the valve 57 produces an IR drop across the resistor section 51a which lowers the voltage on the grid 49c of valve 49 to a value which regulates the voltage output of the armature thyratrons 15 and 16 to a low value, e. g. 50 volts, such that when a directional contactor is subsequently closed, the current supplied to the armature 10a of the motor is limited to approximately full load value.

Also at this point in the operation, the cathode 55b of control valve 55 is connected through the normally closed contacts 72a of relay 72 and conductor 83 to the conductor 47a of the standard voltage source, with the result that the cathode 55b is so positive with respect to its grid that the valve 55 is nearly nonconducting. As pointed out in the foregoing, this causes the valve 54 to be nearly fully conducting, thereby to saturate the field reactor 36 and advance the phase of the grid voltage of the field thyratrons 13 and 14 so that these thyratrons supply full rated current to the shunt field winding 16b, thereby to provide maximum starting torque. Since the field current flows through the operating coil 26a of the field protective relay 26, this relay picks up and closes its normally open contacts 26b. In closing, contacts 26b complete a circuit for the operating coil 85a of a relay 85 which is controlled by the stop push button switch 41 to effect the stopping operation of the motor. This relay is known as the stop relay. The energizing circuit is traced from the low voltage tap 12c through conductor 84, operating coil of stop relay, normally closed contacts 72d of relay 72, normally closed contacts of stop push button 41, contacts 26b of field protective relay 26 to the low voltage tap 12b. Responsive to energization, the stop relay 85 picks up and closes its normally open contacts 85b and opens its normally closed contacts 85c, 85d and 85e. Contacts 85b in closing complete a holding circuit in parallel with contacts 72d of relay 72.

Assuming that it is desired to operate the motor at a speed above base speed within the field weakened range, the knob of the speed controlling potentiometer is moved until the sliders 13a and 14a are in positions between 5 and 9 which correspond to the desired operating speed. This has no immediate effect upon the thyratron valves 13, 14, 15, and 16, since at this point in the operation, these valves are under the control of the preconditioning circuit.

To start the motor in the forward direction, the forward push-button switch 39 is depressed to bridge its normally open contacts 39a, thereby to complete an energizing circuit for the operating coil of the forward contactor 30. This cir-

cuit is traced from the low voltage tap 12b of the supply transformer, through contacts 70a of relay 70, contacts 39a of the forward push-button switch, normally closed contacts of the reverse push-button switch, normally closed contacts 86a of a reverse control relay, normally closed interlock contacts of reverse contactor 31, operating coil of forward contactor 30 to the low voltage tap 12c. In response to energization, the forward contactor 30 closes its main contacts 30f and 30g and its interlock contacts 30h and 30i and opens its interlock contacts 30a, 30b, 30e, 30d and 30j. The main contacts 30f and 30g in closing complete the armature circuit from the positive terminal 28 of the thyatrons through conductor 29, series field winding 10c, contacts 30g, heating element 32a of the overload relay, armature 10a, and contacts 30f to the negative bus 20. At the instant of the closing of forward directional contactor 30, the armature thyatrons 15 and 16 are phased to supply approximately full load current to the armature, owing to the connection of the grid 57c of control valve 57 to point 67a of the voltage divider 67, 68 between bus 61 of the standard voltage source and the positive side 77 of the armature thyatrons 15 and 16. However, the simultaneous opening of interlock contacts 30a interrupts this preconditioning circuit so that for the remainder of the accelerating period, the current supplied by thyatrons 15 and 16 to the armature is controlled by the setting of the slider 60b of the current limit potentiometer to which the grid 57c is connected. Interlock contacts 30h in closing complete an energizing circuit for the operating coil of control relay 72. This circuit is traced from low voltage tap 12c through conductor 84 and the operating coil of relay 72, contacts 30h of the forward contactor, contacts 39a of the forward push button, contacts 70a of control relay 70, and thence to the low voltage tap 12b. In response to energization, relay 72 picks up and closes its contacts 72c to complete a holding circuit for the operating coil 30c of the forward contactor and a sealing-in circuit for its own operating coil in parallel with the contacts 39a of the forward push-button switch which now may be released. Relay 72 in picking up opens its normally closed contacts 72a to interrupt the field preconditioning circuit and closes its contacts 72b to connect the cathode 55b of field control valve 55 to the slider 19a of the preset field potentiometer 19, to provide for weakening the field to the value preset on the potentiometer 19 as the armature current decreases near the end of the acceleration. Following the interruption of the armature preconditioning circuit by the opening of interlock contacts 30a, the armature current builds up at a rate partially determined by the inductance of the D.-C. winding of the armature saturable reactor 34. Contacts 30b in opening interrupt the energizing circuit for the operating coil 70b of control relay 70 which, in response to deenergization, drops out and opens its normally open contacts 70c.

As a result of the completion of the armature circuit, the motor begins to accelerate to a speed determined by the setting of the speed control potentiometer. During acceleration, before the armature countervoltage has built up to a value corresponding to the preset speed which it is desired to maintain, the phase of the grid voltage of the armature thyatrons tends to be fully advanced and hence, the armature thyatrons tend

to supply a current to the armature which is many times full load value. However, the current limiting control acting through valves 57 and 58 decreases the output of the armature thyatrons to the value determined by the setting of the slider of the current limiting potentiometer 60. If, as assumed, the field control has been set for a speed in the field weakened range, then the current limit control acting through valve 58 will tend to maintain full field until the armature current tends to fall below the present limiting value. Thus, during acceleration to a present speed within the field weakened range, the armature voltage is first allowed to build up at a rate determined by the load on the motor and by the value of the armature current which has been set upon the current limiting potentiometer 60 until full armature voltage is reached. At this point, there is a tendency for the armature current to decrease. However, this tendency will make the grid voltage of the valve 58 more negative, thereby decreasing the conductivity of the valve and making the voltage of the grid of valve 54 more negative, with the result that the field thyatrons 13 and 14 will supply less current to the field. This results in maintaining the armature current substantially constant until the preset field weakened speed is reached, at which point the armature current will drop to that value which is necessary to drive the load. Since the system operates to maintain the maximum permissible value of armature current during the acceleration, the load is accelerated to the pre-selected speed in the minimum possible time consistent with the armature current limit at which the control is set to operate.

At a predetermined low armature voltage, the control valve 87 which is connected across the armature in series with the operating coil 88a of relay 88 becomes conducting. Responsively to energization, relay 88 picks up and closes its contacts 88b in parallel with the normally closed contacts 86b and 89b of the reverse and forward control relays 86 and 89, respectively. Once picked up, relay 88 remains picked up until the positive component of armature voltage is subsequently reduced approximately to zero. Negative components of armature voltage introduced by reversals will not cause the relay to drop out since they are blocked by the rectifying action of valve 87.

If it is desired to operate the motor in the reverse direction at the same speed, it is only necessary to depress the reverse push button 40 to open the normally closed contacts 40a and close the normally open contacts 40b. Contacts 40a in opening interrupt the energizing circuit for the operating coil 88c of the forward contactor which, responsively to deenergization, drops out to the open position in which it is illustrated. Contacts 30f and 30g in opening disconnect the armature from the thyatrons 15 and 16, and contact 30d in closing completes the connection of the dynamic braking resistor 73 across the armature terminals, thereby to produce a dynamic braking torque which is effective in decelerating the motor. Contacts 30a in closing again complete the preconditioning circuit between the grid 57c of the armature control valve 57 and the point 67a on the voltage divider between the standard voltage bus 61 and the positive side of the output voltage of the supply valve apparatus, line 77. Whenever the preconditioning circuit is made effective by the reversing contactors being deenergized, valve 57 operates in conjunction with valve

49 to control the output voltage of thyatrons 15 and 16 in much the same manner that valve 50 operates when the thyatrons 15 and 16 are connected to the armature of the motor. An increase in the output voltage of thyatrons 15 and 16 makes the voltage of junction 67a of resistors 67 and 68 less negative with respect to the cathode 57b of valve 57 which increases the conductivity of valve 57, thereby decreasing the conductivity of valve 49 and the saturation of the saturable reactor which decreases the output voltage. Conversely, a decrease in the output voltage of thyatrons 15 and 16 makes the voltage of junction point 67a more negative with respect to the cathode 57b of valve 57. This decreases the conductivity of valve 57 thereby increasing the conductivity of valve 49 and the saturation of the saturable reactor with the result that the output voltage of the thyatrons is correspondingly increased. Since during the preconditioning period the only load on thyatrons 15 and 16 is a resistance load consisting of resistor 69 and the various resistance voltage dividers, controlling the output voltage at a constant low value means holding the phase angle of the thyatron grid voltage at a definite retarded angle, which may be predetermined by proper selection of the circuit components. Thus, the phase of the grid voltage of the armature thyatrons 15 and 16 is regulated to a point that will permit armature current in the order of full load current to flow at the first instant after the reverse contactor 31 picks up to initiate inverter action. Since the sealing-in circuit of the control relay 72 is independent of the contacts of the reversing contactors, relay 72 remains picked up during this reversing period and consequently the cathode 55b of field control valve 55 remains connected to the slider 19a of the field control potentiometer, and thus there is no tendency for the control to strengthen the field prior to the reclosing of the reversing contactors. Thus, the countervoltage of the armature and the conductivity of the armature thyatrons 15 and 16 are both regulated to values which will be favorable to successful inverter operation when the reverse contactor 31 is closed.

The closing of contacts 38b completes an energizing circuit for the operating coil 70b of control relay 70 which, responsively to energization, picks up after a short time delay and closes its contacts 70c to complete an energizing circuit for the operating coil 31c of the reverse contactor 31. This circuit is traced from the conductor 84, through coil 31c, normally closed contacts 39e of the forward contactor, normally closed contacts 89a of forward control relay 89, normally closed contacts 39b of the forward push button, contacts 49b of the reverse push button, and thence by the circuit previously traced to low voltage tap 12c of the supply transformer. The relay 70 has sufficient time delay in its operation to delay the closing of the reverse contactor 31 until the retardation of the phase of the grid voltage of armature thyatrons 15 and 16 is substantially completed.

Responsively to energization, reverse contactor 31 picks up and opens its normally closed interlock contacts 31a, 31b, 31d, 31e and 31f, and closes its main contacts 31f and 31g and its interlock contacts 31h and 31i. Contacts 31h in closing complete a holding circuit for the operating coil 31c independent of the contacts of the reverse push button which may now be released. Contacts 31d in opening interrupt the

dynamic braking circuit, and main contacts 31f and 31g in closing connect the armature 10a to the thyatrons 15 and 16 for the reverse direction of rotation, and since the armature is still rotating in the forward direction, inverter operation ensues. The opening of interlock contacts 31b interrupts the energizing circuit for the operating coil of control relay 70 which responsively to de-energization, drops out and opens its contacts 70a and 70c. Simultaneously, interlock contacts 31a in opening interrupt the preconditioning circuit between the grid 57c of control valve 57 and the point 67a on the voltage divider across the standard voltage source. The control of the armature thyatrons 15 and 16 during the inverter operation is now under the control of the current limit potentiometer 60 to the slider 60b of which the grid 57c of the current limit control valve 57 is connected. Thus, the armature current during inverter operation is limited to the value which is preset upon the current limit potentiometer 60.

The closing of main contacts 31g of the reverse contactor 31 connects the lower armature terminal through conductor 11 to the cathode 13b of the valve 13 in the reverse snubbing circuit. Since the armature 10a is still rotating in the forward direction, the polarity of the countervoltage is unchanged and the lower armature terminal is therefore negative, and this negative voltage is applied to point 75a between which and line 47a is connected a voltage divider consisting of resistors 74 and 75. The values of resistors 74 and 75 are so chosen that the potential of the cathode 13b of valve 13, which is connected to their junction point 74a, reaches the potential of the negative conductor 29 at the same time that the lower terminal of the armature attains its maximum permissible negative value with respect to the negative bus 29. The application of negative voltage to the cathode 13b renders the valve 13 conducting and the resultant voltage drop across the resistor 81, lowers the voltage of the grid 54c of valve 54, thereby decreasing its conductivity and weakening the field of the motor. As a result, the armature countervoltage is kept below the safe limit for inverter operation and at the same time the field strength is maintained as high as possible, consistent with successful inverter operation, to obtain strong reversal torque. Thus, the tendency of the field current limit control valve 58 to strengthen the field as the armature current approaches the preset current limit is counteracted by the reverse snubbing circuit valve 13 during inverter operation.

As a result of the inverter operation, a strong regenerative braking torque is set up, and the speed of the armature is rapidly decelerated to rest. As the armature approaches zero speed, the countervoltage decreases and consequently, the voltage of the cathode 13b again becomes positive and renders the valve 13 nonconducting so that during the ensuing acceleration in the reverse direction, the field control valve 54 is controlled by the field potentiometer 19 and the current limit potentiometer 60 acting through the control valve 58.

A reversal of the operation of the motor from a high field weakened speed to a lower speed is accomplished by depressing the reverse push button 40 and rotating the knob of the preset speed control potentiometers 18 and 19 to a position corresponding to the desired speed for the reverse direction of rotation. In other words, the slider 75 19a of the field potentiometer 19 is moved into

engagement with the contact strip 19b, with the result that the voltage of the cathode 55b of the valve 55 becomes so positive with respect to the grid voltage that the valve 55 becomes nonconducting and the valve 54 tends to become fully conducting. If the valve 54 were permitted to become fully conducting, the field saturable reactor 36 would be fully saturated and the field thyratrons 13 and 14 would supply maximum current to the shunt field winding 16b. In the period following the closing of the reverse contactor 31, this strengthening of the motor field is prevented by the action of the valve 73 in the reverse snubbing circuit as described in the foregoing. However, in the interval in which both forward and reverse contactors 30 and 31 are dropped out preceding the closing of the reverse contactor, the valve 73 is not connected to the armature 19a and is therefore inactive. However, the strengthening of the field during this period in which both forward and reverse contactors are dropped out is prevented by action of the valve 78, the anodes of which are connected through normally closed contacts 30d and 31d, respectively, to opposite terminals of the armature during the period when both reversing contactors are open. During this period, the valve 78 supplies a voltage to the junction point 65a of the resistors 65 and 66 to which the grid 64c of valve 64 is connected. As a result, the valve 64 is rendered conducting, thereby producing a voltage drop across the resistor 62a which lowers the voltage of the grid 54c of the field control valve 54 sufficiently to counteract the tendency of the preset potentiometer 19 to strengthen the field during this period.

As the forward speed of the motor approaches zero, the inverter action ceases and the motor is accelerated in the reverse direction in a manner similar to the forward acceleration described in the foregoing.

Assuming the motor is operating in the forward direction, and that it is desired to stop the motor: The stop push-button switch 41 is depressed to open its normally closed contacts thereby to deenergize the stop relay 85. Responsively to deenergization, the stop relay drops out and opens its normally open contacts 85b and closes its normally closed contacts 85c, 85d, and 85e. Since relay 72 is picked up and will remain picked up until the motor comes to rest, the stop relay cannot be picked up again until the motor comes to rest. Contacts 85d in closing complete an energizing circuit for the operating coil of the reverse relay 86 which extends from low voltage tap 12c through coil of reverse relay 86, normally closed contacts 89c of forward relay 89, normally closed contacts 31j of reverse contactor 31, contacts 85d of stop relay, contacts 72c of relay 72, contacts 88b of relay 88 to low voltage tap 12b. Responsively to energization, reverse relay 86 picks up and opens its normally closed contacts 86a, 86b, and 86c and closes its normally open contacts 86d and 86e. Contacts 86a in opening deenergize the forward contactor which thereupon drops out and disconnects the armature from the thyratrons 15, 16. As a result, the relay 70 is again energized over the circuit previously traced and picked up after a small delay to close its contacts 70a and 70c. This completes an energizing circuit for the reverse contactor which is traced from low voltage tap 12b through contacts 70a and 86e, normally closed contacts of forward push button, normally closed contacts 89a of forward relay, normally closed contacts 30e of for-

ward contactor and coil of reverse contactor to low voltage tap 12c. In response to energization, reverse contactor picks up and closes its main contacts 31f and 31g to connect the armature to the thyratrons 15 and 16 for the reverse operation. However, at this point the armature is still rotating in the forward direction and consequently, inverter action ensues, as explained in the foregoing in connection with the reversal operation. The inverter operation produces a strong braking torque which rapidly decelerates the motor. The reverse contactor in picking up energizes control relay 90. The circuit is traced from low voltage tap 12c through coil 90a, contacts 70c of relay 70, contacts 31i of reverse contactor, normally closed contacts 85c of stop relay to the low voltage tap 12b. Responsively to energization, relay 90 picks up and closes its contacts 90b to complete a sealing-in circuit in parallel with contacts 70c and 31i, and also closes its contacts 90c and opens its normally closed contacts 90d.

In the closed position of the reverse contactor, contacts 31b are open and deenergize relay 70 which drops out responsively to deenergization. Contacts 90d in opening disconnect the cathode 50b of the armature control valve 50 from the slider 18a of the preset speed potentiometer 18, and contacts 90c in closing connect the cathode 50b to the negative bus 20. This is equivalent to setting the slider 18a at the zero speed position, and if the grid voltage, which is a measure of the armature voltage, remained unchanged at this point the valve 50 would become fully conducting with the result that the armature thyratrons 15 and 16 would be rendered nonconducting before the motor had been braked to rest. However, when the reverse contactor 31 closed, the grid 50c of valve 50, which was previously connected to the positive terminal of the armature, is now connected to the negative terminal and the conduction of valve 50 is maintained at a low value with the result that the grid voltages of thyratrons 15 and 16 are controlled to maintain the inverter operation, thereby to continue the rapid deceleration of the motor. As the deceleration continues, the negative grid voltage of valve 50 is correspondingly decreased so that at zero speed the thyratrons 15 and 16 are phased off and cease conducting.

As soon as the thyratrons 15 and 16 are phased off, the valve 87 ceases to conduct, thereby deenergizing relay 88. Responsively to deenergization, relay 88 drops out and deenergizes relay 72 which thereupon drops out and opens its contacts 72b and 72c and closes its contacts 72a and 72d. Contacts 72c in opening deenergize the reverse contactor 31 and the reverse relay 86. Responsively to deenergization, the reverse contactor drops out to disconnect the armature from the thyratrons 15, 16. Contacts 72d in closing complete the energizing circuit for the stop relay 85, which picks up to close its contacts 85b and to open its contacts 85c, 85d, and 85e. Contacts 85b in closing complete a sealing-in circuit, and contacts 85c in opening deenergize the relay 90 which drops out to open contacts 90b and 90c and to close contacts 90d, thereby leaving the control in a reset condition.

Although in accordance with the provisions of the patent statutes this invention is described as embodied in concrete form and the principle thereof has been explained, together with the best mode in which it is now contemplated applying that principle, it will be understood that alterations and modifications will readily suggest themselves to persons skilled in the art without

departing from the true spirit of this invention or from the scope of the annexed claims.

What we claim as new and desire to secure by Letters Patent of the United States is:

1. Control apparatus for an electric motor comprising in combination, means for controlling the supply of direct current to an electric motor comprising electric valve apparatus provided with a control grid, a standard voltage source, means for presetting an operating speed for said motor comprising means for deriving a predetermined reference voltage from said source, means for producing a signal voltage proportional to the speed of said motor, and means responsive to the difference of said derived voltage and signal voltage for varying the conductivity of said valve means in accordance with said difference, means for limiting the current supplied to said motor to a predetermined value comprising a control circuit carrying current proportional to the current supplied to said motor and a control electric valve connected to control the grid circuit of said valve means and having a grid connected to said control circuit, reversing switching means in the output circuit of said valve means, and means responsive to said switching means when said switching means is open for directly connecting the grid of said control valve to the output circuit of said valve apparatus to adjust the conductivity of said valve means for inverter operation in response to operation of said switching means to effect reversal of said motor.

2. Control apparatus for an electric motor comprising in combination, electric valve means for controlling the supply of direct current to an electric motor, means for limiting the current supplied to said motor to a predetermined value comprising a control circuit carrying current proportional to the armature current of said motor, a control electric valve for controlling said electric valve means and having a control grid connected to said control circuit, a standard voltage source, switching means in the output circuit of said valve means, means responsive to said switching means when said switching means is open for directly connecting the grid of said control valve to the output circuit of said valve means to adjust the conductivity of said valve to a predetermined value, and an auxiliary electric valve having an anode connected to the cathode of said control valve and a cathode connected to the grid of said control valve to render said auxiliary valve conducting and thereby limit the negative voltage applied to the grid of said control valve at low armature current of said motor.

3. A control system for an electric motor comprising in combination, electric valve means provided with a control grid for controlling the supply of direct current to an electric motor, a standard voltage source, means for presetting an operating speed for said motor comprising means for deriving a predetermined reference voltage from said source, means for producing a signal voltage proportional to the speed of said motor, and means responsive to the difference of said derived voltage and signal voltage for varying the firing point of said valve means in accordance with said difference, means for limiting the current supplied to said motor to a predetermined value comprising an auxiliary electric valve having a grid connected to be responsive to the current supplied to said motor and having its output circuit connected to control the firing point of said valve means, reversing switching means for selecting the polarity of the voltage supplied

to said motor to control the direction of rotation, and means responsive to said switching means when said switching means is open for directly connecting the grid of said auxiliary valve to the output circuit of said electric valve means to retard said firing point to limit the current supplied to said motor before said current limiting means becomes fully effective, and relay means operatively associated with said reversing switching means for preventing the reversal operation of said reversing switching means for the period of time required for said retarding means to become effective.

4. A control system for an electric motor comprising in combination, first electric valve means for controlling the supply of direct current to the armature of said motor, additional electric valve means provided with a control grid for controlling the supply of direct current to the field of said motor, forward and reverse control devices and reversing switching means controlled thereby in the output circuit of said first valve means for controlling the direction of rotation of said motor, a stop control device for controlling the opening and closing of said switching means, means responsive to the opening operation of said switching means for controlling said additional valve means to strengthen the field of said motor, and means for preventing the strengthening of said field when said switching means is open during a reversal of said motor by said reversing switching means.

5. A control system for an electric motor comprising in combination, a first electric valve means for controlling the supply of direct current to the armature of the motor, additional electric valve apparatus provided with a control grid for controlling the supply of direct current to the field of said motor, forward and reverse control devices and directional contactors in the output circuit of said first electric valve means controlled by said control devices for controlling the polarity of the voltage supplied to said armature to control the direction of rotation, a stop control device for controlling said contactors to interrupt the output circuit of said first electric valve means, an electromagnetic switching device responsive to the closing operation of either of said contactors and having a sealing in circuit independent of said contactors for controlling said additional valve means to maintain the field of said motor at its existing strength when said reversing contactors are open during a reversal operation, and means responsive to stopping of said motor following an operation of said stop control device for interrupting said sealing in circuit to cause said electromagnetic switching device to control said additional valve means to strengthen the field of said motor.

6. A control system for an electric motor comprising in combination, first electric valve means for supplying direct current to the armature of the motor, additional electric valve means for supplying direct current to the field of said motor, reversing switching means for connecting the armature of said motor to said first valve means for rotation in either direction, and means responsive to the armature voltage of said motor following a reversal of the connections of said armature to said first valve means for controlling said additional valve means to vary the excitation of said motor to limit the armature voltage of said motor to a predetermined value.

7. A control system for an electric motor comprising in combination, first electric valve means

for supplying direct current to the armature of the motor, additional electric valve means for supplying direct current to the field of said motor, means for controlling said additional valve means comprising a control valve provided with a control grid and means for supplying a variable control voltage to said grid, reversing switching means for connecting said armature to said valve means for rotation in either direction, and means for limiting the armature voltage of said motor to a predetermined value following operation of said switching means to reverse the connection of said armature to said first valve means comprising a second control valve having an anode, cathode, and control grid and connections from the cathode and grid of said second control valve to said armature and connections from the anode-cathode circuit of said second valve to the grid of said first valve to control said first valve to limit the excitation of said motor field.

8. A control system for an electric motor comprising in combination, first electric valve means for supplying direct current to the armature of the motor, additional electric valve means for supplying direct current to the field of said motor, means for controlling said additional valve means comprising a control valve provided with a control grid and means for supplying a variable control voltage to said grid, reversing switching means for connecting said armature to said first valve means for rotation in either direction, and means for limiting the armature voltage of said motor to a predetermined value following operation of said switching means to reverse the connection of said armature to said first valve means comprising a second control valve having an anode, cathode, and control grid and connections from the cathode of said second control valve to the positive terminal of said armature and from the grid of said control valve to the negative terminal of said armature during normal running operation of said motor thereby to maintain said second control valve inactive, said reversing switching means serving to reverse said grid and cathode connections upon reversal of the connections from said armature to said first valve means thereby to render said second control valve conducting while the voltage of said armature is reversing and nonconducting when the reversal of said armature voltage is completed, and a connection from the anode of said second control valve to the grid of said first control valve to control said first control valve to limit the excitation of said motor during said reversal operation.

9. A control system for an electric motor comprising in combination, first electric valve means for supplying direct current to the armature of said motor, additional electric valve means for supplying direct current to the field of said motor, means responsive to armature current for controlling said additional electric valve means to strengthen the field of said motor to limit the armature current to a predetermined value, reversing switching means for connecting said armature to said first valve means for rotation in either direction, and means responsive to the armature voltage of said motor following a reversal of the connections of said armature for counteracting the action of field strengthening means thereby to control said additional valve means to vary the excitation of said field to limit the armature voltage to a predetermined value until the reversal of said armature voltage is completed.

10. A control system for an electric motor comprising in combination, electric valve apparatus for supplying direct current to the armature of said motor, additional electric valve apparatus for supplying direct current to the field of said motor, a speed control device for controlling said additional valve means to vary the excitation of said motor field, reversing switching mechanism for connecting said armature to said first electric valve means for rotation in either direction, and means responsive to the armature voltage of said motor during the period in which the armature is disconnected from said first valve means during a reversing operation for controlling said second valve means to prevent strengthening the field of said motor by said speed control device in a reversal of said motor from a high speed to a relatively lower speed.

11. A control system for an electric motor comprising in combination, electric valve apparatus for supplying direct current to the armature of said motor, additional electric valve apparatus for supplying direct current to the field of said motor, a dynamic braking resistor, forward and reverse directional contactors for connecting said armature to said first electric valve means for rotation in either direction and provided with normally closed contacts for connecting said dynamic braking resistor across said armature when said armature is disconnected from said first valve means, a speed control device for controlling said additional valve means to vary the excitation of said motor field, and means for preventing strengthening the field of said motor when said armature is disconnected from said first valve means during a reversal of said motor from a high speed to a relatively lower speed comprising a full wave rectifier valve having a pair of anodes connected to points on said braking resistor of opposite polarity and having its cathode connected to an intermediate point on said resistor, a voltage drop device connected in the output circuit of said full wave rectifier, and means responsive to the voltage across said voltage drop device for controlling said second valve means.

12. Control apparatus for an electric motor comprising electric valve apparatus for supplying a rectified voltage to the armature of the motor, reversing switching means for connecting said armature to said valve apparatus for rotation in either direction, a stop control device, means responsive to operation of said stop control device for controlling said reversing switching means to reverse the connections of said armature to said electric valve apparatus to provide for inverter operation of said valve apparatus to brake said motor to rest, and means responsive to a predetermined low speed of said motor to disconnect said motor from said valve apparatus.

13. Control apparatus for an electric motor comprising electric valve apparatus for supplying a rectified voltage to the armature of the motor, reversing switching means for connecting the armature of the motor to said electric valve apparatus for rotation in either direction, means for producing an adjustable reference voltage, means for producing a signal voltage having a predetermined relationship to the speed of said motor, means responsive to the difference of said voltages for controlling said electric valve apparatus to effect operation of said motor at a speed corresponding to said reference voltage, a stop control device, means responsive to operation of said stop control device for controlling said re-

versing switching means to reverse the connections of said armature to said valve apparatus, means responsive to operation of said switching means to adjust said reference voltage for zero speed of said motor, and means responsive to a predetermined low speed of said motor for controlling said reversing switching means to disconnect said armature from said valve apparatus.

14. Control apparatus for an electric motor comprising electric valve apparatus for supplying a rectified voltage to the armature of said motor, reversing switching means for connecting said armature to said valve apparatus for rotation in either direction, a source of adjustable reference voltage, means for deriving a voltage from the 10 countervoltage of said motor, means responsive to the difference of said reference voltage and said derived voltage for controlling said valve apparatus to effect operation of said motor at a

5

speed corresponding to said reference voltage, a stopping control device, means responsive to operation of said stopping control device for controlling said reversing switching mechanism to reverse the connections of said armature to said electric valve apparatus, an electromagnetic switching device responsive to the reversal operation of said reversing switching means for adjusting said reference voltage for zero speed, an electric valve connected to be responsive to the countervoltage of said motor and an electromagnetic switching device controlled thereby for controlling said reversing switching means to disconnect said armature from said electric valve apparatus at a predetermined low speed of said motor.
